FRANK L. VAN DUSEN, OF FORT ERIE, ONTARIO, CANADA.

IGNITING DEVICE.

1,184,280.

Specification of Letters Patent.

Patented May 23, 1916.

Application filed May 16, 1913, Serial No. 768,035. Renewed October 20, 1915. Serial No. 57,008.

To all whom it may concern:

Be it known that I, FRANK L. VAN DUSEN, a citizen of the United States of America, and a resident of the village of Fort Erie, 5 Ontario, Canada, have invented certain new and useful Improvements in Igniting Devices, of which the following is a full, clear, and exact description.

My invention relates generally to igniting devices and more particularly to devices which produce ignition by the frictional contact of two metals.

The principal object of my invention has been to provide a device which may be applied to lamps, gas burners and the like for automatically lighting the same.

Another object has been to provide a device which shall be simple to operate and inexpensive to manufacture.

Reference is to be had to the accompanying drawings forming part of this specification, in which I show my invention as applied to an oil burner and in which like characters of reference indicate like parts, 25 throughout the several views of which:

Figure 1 is a plan view of my device with a portion of the base of the burner broken away. Fig. 2 is a side elevation of the same, partly broken away in section on line 30 2—2 of Fig. 1. Fig. 3 is a fragmentary sectional view taken on line 3—3 of Fig. 1.

In the drawings, 5 represents the oil burner of an ordinary lantern; 6 the fuel receptacle for the same which is carried by 35 the usual base 7. The burner 5 is provided with the usual wick tube 8 and wick raiser 9.

The spark in my device is produced by the friction wheel 10 against which is frictionally held, a piece of pyrophorous metal 12. 40 The wheel 10 is carried by a shaft 11, mounted to rotate within the oil receptacle 6 of the lantern. This piece of metal 12 is slidably disposed within a sleeve 13 and pressed against the friction wheel 10 by a helical spring 14 disposed within the sleeve 13 and having its outer end bearing against an adjusting screw 15 interiorly screw-threaded to said sleeve. The sleeve 13 is preferably supported upon a standard 16. 45 secured to the top of the fuel receptacle 6. The shaft 11 passes through a sleeve 17 formed within the fuel receptacle 6 and has disposed at its lower end a gear pinion 18. Meshing with the gear pinion 18 is a driving gear 19 which is carried at the lower 50 end of the shaft 20 mounted in suitable bear-

ings carried by the lantern parts. Rotatably carried by the shaft 20 and disposed directly over the gear 19 is a ratchet 21, having secured thereto an operating arm 22. 60 The operating arm has secured at its outer end an upwardly extending stem 23 which extends up through a slot (not shown) in the base 7 of the lantern, whereby said arm may be operated. A spring 24 has one end secured to the arm 22 and the other end secured to any suitable portion of the lantern base, whereby the said arm will be retracted and held in its normal position, as shown in the drawings. A ratchet pawl 25 70 is carried by the operating gear 19 and has its outer end pressed into engagement with the ratchet 21 by means of a suitable spring 26.

A torch 27 is normally disposed within 75 a casing 28 containing some suitable volatile igniting fluid, such as gasolene, or containing some suitable soft packing 29 saturated with the igniting fluid. The casing 28 is located near the wick tube 8 and is preferably provided with spring means disposed beneath the packing 29, whereby the same is always held in contact with the lower end of the torch 27. The lower end of the torch 27 has preferably secured thereto a small 80 tuft of asbestos or other non-inflammable material which is always saturated with volatile fluid and is therefore ignited by the sparks coming from the pyrophorous metal, after it has been raised into the ignition 90 field. The torch 27 is provided at its upper end with a member 30 which forms a cover or cap for the casing 28. The torch 27 is rigidly secured to the outer end of a crank-shaped arm 31, formed on the inner end of 95 the shaft 32 which has also formed at its outer end a crank-shaped arm 33. At the upper end of the shaft 20 is secured a collar 34 which carries near its periphery a U-shaped member 35. This member engages 100 with the outer end of the crank-shaped arm 33 which is oscillated by said member as the same is rotated by the collar 34.

When my device is to be operated, the wick of the burner is turned up so that the 105 upper end projects above the tube 8. The arm 22 is now rotated by means of the stem 23, thus operating the gear 19 and shaft 20. As the shaft 20 is rotated through a portion of its circumference, the U-shaped member 35 carried by the collar 34 will 110 partially rotate the shaft 32 and raise the

torch 27 from the receptacle 28 and carry it into the ignition field. As the gear 19 is rotated the friction wheel 10 will also be rotated through the medium of the gear 18 and shaft 11. The piece of pyrophorous metal 12 contacting with the friction wheel 10 causes a series of sparks to be thrown toward the torch 27, thus igniting the same. When the torch is lighted the wick of the burner will be ignited therefrom. The arm 22 is then released and the spring 24 draws it back to its normal position. At the same time the torch 27 is carried back into the receptacle 28 and the receptacle is closed by 15 the member 30.

Clearly my invention when applied to the oil burner of a lamp or lantern provides a means for lighting the same without removing the globe or chimney surrounding the wick. Therefore, the ignition of the lamp or lantern cannot be affected by outside drafts of air and can be quickly and with certainty accomplished in any kind of atmospheric conditions without the use of 25 matches.

Obviously, some modifications of the details herein shown and described may be made without departing from the spirit of my invention or the scope of the appended 30 claims and I do not wish to be limited to the exact embodiment herein shown and described.

Having thus described my invention, what I claim is:

35 1. The combination of an oil burner provided with a fuel receptacle, a wick and a wick raiser, of an igniting device comprising a torch adjacent to said wick, said torch being pivotally carried by a stationary member and movable into an ignition field, a rotatably mounted friction wheel arranged to discharge sparks into the ignition field and a piece of pyrophorous metal held in frictional contact with said wheel.

45 2. The combination of an oil burner provided with a fuel receptacle, a wick and a wick raiser, of an igniting device comprising a pivotally mounted torch adjacent to said wick and movable into an ignition field, said torch being of refractory material and having its igniting end normally disposed in contact with the igniting fluid, a rotatably mounted friction wheel arranged to discharge sparks into the ignition field and a piece of pyrophorous metal held in frictional contact with said wheel.

55 3. The combination of an oil burner provided with a fuel receptacle, a wick and a wick raiser, of an igniting device comprising a pivotally mounted torch adjacent to said wick, said torch being movable into and away from a receptacle containing the igniting fluid, and also movable into an ignition field, a rotatably mounted friction wheel arranged to discharge sparks into the igni-

tion field and a piece of pyrophorous metal held in frictional contact with said wheel.

4. The combination of an oil burner provided with a fuel receptacle, a wick and a wick raiser, of an igniting device comprising a stationary torch casing containing packing saturated with volatile fluid, a pivotally mounted torch carried by a stationary member and movable into an ignition field, said torch being normally disposed within said casing and in contact with said packing, a rotatably mounted friction wheel arranged to discharge sparks into the ignition field and a piece of pyrophorous metal held in contact with said wheel.

5. The combination of an oil burner provided with a fuel receptacle, a wick and a wick raiser, of an igniting device, comprising a stationary torch casing located adjacent to said wick and containing packing saturated with volatile fluid, a pivotally mounted torch held normally in contact with said packing in said casing and movable into an ignition field, a cover for said casing carried by said torch, a rotatably mounted friction wheel arranged to discharge sparks into the ignition field and a piece of pyrophorous metal held in frictional contact with said wheel.

85

90

6. The combination of an oil burner provided with a fuel receptacle, a wick and a wick raiser, of an igniting device comprising a torch adjacent to said wick, said torch being pivotally carried by a stationary member and movable into an ignition field, a rotatably mounted friction wheel arranged to discharge sparks into the ignition field, a piece of pyrophorous metal held in frictional contact with said wheel, means for operating said frictional wheel and means for moving said torch into and out of the ignition field.

95

100

105

7. The combination of an oil burner provided with a fuel receptacle, a wick and a wick raiser, of an igniting device comprising a torch adjacent to said wick, said torch being pivotally carried by a stationary member and movable into an ignition field, a rotatably mounted friction wheel arranged to discharge sparks into the ignition field, a piece of pyrophorous metal held in frictional contact with said wheel, means for operating said friction wheel and means for simultaneously moving said torch into the ignition field.

110

115

120

8. The combination of an oil burner provided with a fuel receptacle, a wick and a wick raiser, of an igniting device comprising a pivotally mounted torch adjacent to said wick, said torch being movable into and away from a receptacle containing the igniting fluid, and also movable into an ignition field, a rotatably mounted friction wheel arranged to discharge sparks into an ignition field, a piece of pyrophorous metal held in

125

130

frictional contact with said wheel, means for operating said friction wheel and means for simultaneously moving said torch into the ignition field.

5 9. The combination of an oil burner provided with a fuel receptacle, a wick and a wick raiser, of an igniting device comprising a torch adjacent to said wick, said torch being pivotally carried by a stationary member and movable into an ignition field, a rotatably mounted friction wheel arranged to discharge sparks into the ignition field, a piece of pyrophorous metal held in frictional contact with said wheel, and gear and 10 ratchet means for imparting motion in one direction to said friction wheel and in both directions to said torch.

10 10. The combination of an oil burner provided with a fuel receptacle, a wick and a wick raiser, of an igniting device comprising a torch adjacent to said wick and movable into an ignition field, a rotatably mounted friction wheel arranged to discharge sparks into the ignition field, a piece of pyrophorous metal held in frictional contact with said wheel, gear and ratchet means for imparting motion in one direction to said friction wheel and in both directions to said torch and means located in the base of 25 said fluid receptacle for actuating said gear and ratchet means.

11 11. The combination of an oil burner provided with a fuel receptacle, a wick and a wick raiser, of an igniting device, comprising a stationary torch casing located adjacent to said wick and containing packing saturated with volatile fluid, a pivotally mounted torch held normally in contact with the packing in said casing and movable 30 into an ignition field, a cover for said casing carried by said torch, a rotatably mounted friction wheel arranged to discharge sparks into the ignition field, a piece of pyrophorous metal held in frictional contact with 35 said wheel and gear and ratchet means for imparting motion in one direction to said friction wheel and in both directions to said torch.

12 12. The combination of an oil burner provided with a fuel receptacle, a wick and a wick raiser, of an igniting device comprising a torch casing located adjacent to said wick, a cover for said casing, a pivotally mounted torch carried by a stationary member and having a tuft of refractory substance secured thereto and arranged to move 50 into and out of said casing and ignition field, a porous refractory substance disposed in said casing and saturated with volatile fluid, a cover for said casing carried by said torch, a spring in said casing for holding 55

said last mentioned substance up and in contact with the torch tuft, a rotatably mounted friction wheel arranged to discharge sparks against said torch when the same is raised 60 to the igniting position, a piece of pyrophorous metal held in frictional contact with said wheel, gear and ratchet means for producing the rotation of said wheel and mechanism actuated by said gear means 65 to raise said torch into the igniting position coincidentally with the production of the sparks and for returning said torch to its normal position and for closing said cover onto said casing for extinguishing the torch. 70 75

13. In combination with the burner of a lamp, mechanism for producing ignition comprising a receptacle for containing a substance ignitable from a friction spark, a cover for said receptacle, an extension on 80 said cover carrying a refractory tuft to contact with the contents of said receptacle, a friction disk mounted to rotate and discharge sparks against said tuft when in the exposed position, an adjustable contacting piece bearing against said disk, and gearing and ratchet mechanism for imparting motion in one direction to said disk and in both directions to said cover and extension.

14. In combination with the burner of a lamp, an ignition device comprising a tube closed at its lower end and having its open upper end adjacent to the wick of the burner of said lamp, a cap for said tube, an extension on said cap for carrying a tuft of refractory substance and positioned to move in and out of said tube, a refractory, porous substance in said tube, a spring in said tube for holding said substance up and in contact with said tuft, a friction disk for discharging 90 sparks against said tuft when the same is raised to the open position, a friction piece in contact with said disk, a spring and screw for regulating the pressure of said piece against said disk, gearing and ratchet mechanism for producing rotation of said disk in the direction to discharge sparks against 95 said tuft and mechanism actuated by said gearing mechanism to raise said tuft into the ignition position coincidentally with the production of the spark, and for returning said tuft to its normal position and for closing said cap over said tube to extinguish the burning of said tuft after the lamp wick has been ignited. 100 105 110 115

In testimony whereof, I have hereunto signed my name in the presence of two subscribing witnesses.

FRANK L. VAN DUSEN.
